DESIGN FOR A SWINGING TARGET TOY

Anthony Schillace and William J. Daily, Girard,
Pa., assignors to Louis Marx & Company, Inc.,
New York, N. Y., a corporation of New York

Application March 7, 1940, Serial No. 90,750

Term of patent 14 years

To all whom it may concern:

Be it known that we, Anthony Schillace and William J. Daily, citizens of the United States and residents of Girard, in the county of Erie and State of Pennsylvania, have invented a new, original, and ornamental Design for a Swinging Target Toy, of which the following is a specification, reference being had to the accompanying drawing, forming a part thereof, wherein:

Fig. 1 is a top plan view of a swinging target toy, showing our new design;

Fig. 2 is a front elevational view thereof; and

Fig. 3 is a side elevational view.

We claim:

The ornamental design for a swinging target toy, substantially as shown.

ANTHONY SCHILLACE.

WILLIAM J. DAILY.
